UNITED STATES PATENT OFFICE

137,882

DESIGN FOR A STROLLER

Claude Wells, Milwaukee, Wis.

Application September 1, 1943, Serial No. 111,038

Term of patent 7 years

(Cl. D14—14)

To all whom it may concern:

Be it known that I, Claude Wells, a citizen of the United States, residing at Milwaukee, in the county of Milwaukee and State of Wisconsin, have invented a new, original, and ornamental Design for a Stroller, of which the following is a specification, reference being had to the accompanying drawing, forming part thereof.

In the drawings:

I claim:

The ornamental design for a stroller, as shown.

CLAUDE WELLS.
